CLAIM

The ornamental design for a sound bar, as shown and described.

DESCRIPTION

1. Sound bar

1.1 : Perspective

1.2 : Front

1.3 : Back

1.4 : Left

1.5 : Top

1.6 : Bottom

1.7 : Perspective

The broken lines depict portions of the sound bar and environmental subject matter which form no part of the claimed design. Reproduction 1.7 shows the sound bar in a state of use, wherein the broken line showing of a screen depicts environmental subject matter which forms no part of the claimed design.

Reproduction 1.1 is a front perspective view of the sound bar; reproduction 1.2 is a front view thereof; reproduction 1.3 is a back view thereof; reproduction 1.4 is a left view thereof, where the right view is a mirror image; reproduction

(Continued)

1.5 is a top view thereof; reproduction **1.6** is a bottom view thereof; and reproduction **1.7** is a perspective view thereof.
